UNITED STATES PATENT OFFICE.

WILLIAM D. SOUTHARD, OF PEEKSKILL, ASSIGNOR TO SOUTHARD, ROBERT-
SON & CO., OF NEW YORK, N. Y.

DESIGN FOR A STOVE.

SPECIFICATION forming part of Design No. 22,464, dated May 23, 1893.

Application filed April 11, 1893. Serial No. 469,989. Term of patent 14 years.

To all whom it may concern:

Be it known that I, WILLIAM D. SOUTHARD, a citizen of the United States, and a resident of Peekskill, in the county of Westchester and State of New York, have invented and produced a new and original Design for a Stove, of which the following is a specification.

My stove is represented in the accompanying drawings, in which—

10 Figure I is a perspective view of the same. Figs. II, III, IV and V are enlarged details of the ornamentation.

The legs of the stove are of the form shown, having fret-ornamentation *h* in the upper portions, and flat ornamentation of the lower portions as shown. The bottom *b* is of general contour, having a somewhat beveled drooping edge, round corners, and a slight core extending around the corner of the upper edge. All 15 parts are void of further ornamentation, except that imparted by the raised portion *l*, to receive the base. Around the bottom of said portion a bead *m* is run, extending around and under the ash-pit door. The said door, 20 *p*, is placed at the bottom at *n*. The door *p* bears a name plate on its bottom extension, and the ornamentation in the space *y* is as represented in Fig. III. The door is otherwise ornamented in keeping with the base, 25 and constitutes the front side thereof.

The base *c* is of general form, bearing two rows of ornamentation *r*, *w*, on its sides, the former as represented in Fig. III, and the lat-

ter as shown in Fig. II. The top corners are ornamented with figures *u*, as shown in Fig. V. 35

The fire and clinker door frames are of scroll outlines as shown, with beaded facings. They are provided with entablature-like projections *o*, *o*, above the door openings, and a like projection *o'* inverted is provided on the lower 40 edge of the fire door opening.

The fire door *e'* is shown in enlarged, cross-section in Fig. 1. The clinker door *e* is similar to the fire door, except that it is not so high, and contains a single row of lights. 45

The base of the top, *f'*, shown in cross-section in Fig. 1, presents a drooping edge, cored at the upper corner, and bearing ornamentation *t*, as in Fig. IV. The top *f*, rises in ovoid and ogee curves nearly to a point, and is surrounded with an urn *g*. There are two rows of ornamentation on this top, shown at *r*, *s*, and enlarged in Figs. II and III. The two parts forming the top, *f'*, and *f*, and the urn and bowl, are shown in cross-section in Fig. 1. 55

What I claim is—

The design for a stove substantially as herein shown and described.

Signed at Peekskill, in the county of Westchester and State of New York, this 9th day of January, A. D. 1893. 60

WM. D. SOUTHARD.
